CLAIM

The ornamental design for an pair of attachments for weight rack, as shown and described.

DESCRIPTION

FIG. 1 is a top, front, left perspective view of a first embodiment of a pair of attachments for weight rack, with the additional attachment shown removed for clarity of disclosure, showing my new design;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof;

FIG. 8 is a top, front, right perspective view of a pair of attachments for weight rack showing my new design of FIGS. 1-7 in its exemplary environment, showing the pair of attachments for weight rack mounted in a first configuration and a second configuration;

FIG. 9 is a top, front, left perspective view of a second embodiment of a pair of attachments for weight rack, with the additional attachment shown removed for clarity of disclosure, showing my new design of FIGS. 1-7 with selected features disclaimed;

FIG. 10 is a top view thereof;

FIG. 11 is a bottom view thereof;

FIG. 12 is a left side view thereof;

FIG. 13 is a right side view thereof;

FIG. 14 is a rear view thereof;

FIG. 15 is a front view thereof; and,

FIG. 16 is a top, front, right perspective view of a pair of attachments for weight rack showing my new design of FIGS. 9-15 in its exemplary environment, showing the pair of attachments for weight rack mounted in a first configuration and a second configuration.

The broken lines depicting the remainder of the pair of attachments for weight rack show portions that form no part of the claimed design. The broken lines depicting exemplary environment in FIGS. 8 and 16 also form no part of the claimed design.

1 Claim, 10 Drawing Sheets
